Patented Sept. 20, 1921.

UNITED STATES PATENT OFFICE.

MILTON TIBBETTS, OF DETROIT, MICHIGAN, ASSIGNOR TO PACKARD MOTOR CAR COMPANY, OF DETROIT, MICHIGAN, A CORPORATION OF MICHIGAN.

INDICATOR MECHANISM.

1,391,146.

Specification of Letters Patent. Patented Sept. 20, 1921.

Application filed December 16, 1914. Serial No. 877,539.

To all whom it may concern:

Be it known that I, MILTON TIBBETTS, a citizen of the United States, and resident of Detroit, Wayne county, State of Michigan, have invented certain new and useful Improvements in Indicator Mechanism, of which the following is a specification.

This invention relates generally to indicator mechanism.

- 10 One of the objects of the invention is to provide an indicator mechanism that will indicate one of several liquid levels in various tanks or compartments. Usually the lower liquid level is indicated.
- 15 In one form of the invention, a tank is formed with a partition dividing it into two compartments, and an indicator has floats in the two compartments so that either of the liquid levels may be observed.
- 20 Other objects than the one stated above will appear from the description of the embodiment of the invention shown herein, and taken in connection with the drawings, in which the figure represents a tank and indicator embodying the invention.

A motor vehicle gasoline tank 10 is illustrated. It is somewhat elongated and is provided adjacent its middle portion with a partition 11, which may for the purpose of 30 strengthening the tank and preventing undue splashing of the liquid in the tank, extend from top to bottom of the tank. At a suitable point above the bottom of the tank, the partition 11 is provided with one or more 35 openings 12 so that when one of the compartments of the tank is filled through the filler opening 13 the liquid will flow readily into the other compartment and fill it also. Thus the partition 11 is effective for sepa-

40 rating the liquid in the two compartments only below the openings 12, and the principal function of this partition is to thus divide the tank into separate compartments so that the liquid cannot be entirely withdrawn 45 from the tank through a connection to one compartment only. In other words, a reserve supply is retained in the other compartment.

Means are provided for withdrawing the 50 liquid from the compartments separately, so that one will always be maintained in reserve. This means comprises a suction pipe 14, a valve 15, and pipes 16 and 17 leading

respectively to the bottoms of the two compartments. Suitable screens 18 are arranged 55 around the suction ends of the pipes 16 and 17 to thus strain the liquid as it is withdrawn. It will be observed that because of the form of the passageway 19 in the valve 15, the pipe 14 may be connected with either 60 of the pipes 16 or 17, but not with both of them at the same time.

It will be understood that instead of suction means being used, the tank may be supplied with pressure and the liquid will flow 65 out through the pipes 16, 17 and 14 similarly as though by suction.

With the construction so far described, it will be clearly understood that if the tank is filled with liquid and the valve 15 is in 70 the position shown in the drawing, the liquid will be withdrawn from the tank as a whole down to the openings 12 in the partition 11. From that level downwardly the liquid will 75 be withdrawn only from the left hand compartment, and as soon as it is exhausted, the operator will become aware of that fact by the stopping of the motor which may be using the fuel from the tank. The valve 15 may then be switched over so that the passage 19 connects with the pipe 17 and the liquid in the right hand compartment may 80 then be withdrawn. Without changing the position of the valve 15, the tank may be re-filled and the liquid will then be withdrawn 85 from the tank as a whole down to the point 12 and from that level downwardly, it will be withdrawn from the right hand compartment. As soon as that is exhausted, the valve 15 may be shifted over to the pipe 16 90 and the reserve liquid in the left hand compartment may be used.

From the above, it will be observed that first one compartment and then the other acts as the reserve compartment, and if the 95 ordinary level indicator were used in either compartment, it would not indicate the level of the liquid below the opening 12 except in the particular compartment in which it was located. The present invention is designed 100 to indicate the level of the liquid in either of said compartments, and preferably the lower level.

The indicator mechanism will now be described. An indicator device is shown as 105 comprising a casing 20 secured to the top

of the tank 10. This casing 20 incloses a gear wheel 21 upon which is mounted a pointer 22 which is adapted to indicate through the glass window 23 the level of the liquid in the tank. As shown, this pointer always indicates the lower level where the level is different at one end of the tank than at the other.

A support 24 is also suitably mounted on the tank 10 and its upper end extends into the casing 20, the joint between the casing, the support, and the tank, preferably being a sealed joint so that the tank may be used under pressure. The support 24 also extends downwardly into the tank adjacent the middle thereof, preferably immediately at one side of the partition 11, and a vertical rack bar 25 is mounted in the support and arranged to mesh with the gear wheel 21. Gravity tends to hold this rack bar in lower position and thus cause the hand 22 to indicate the full condition of the tank, but for the purpose of overcoming any friction that may be present to cause the rack bar to stick, a spring 26 is provided to yieldingly hold the rack bar down. It will be understood that this spring is very light so that the floats hereinafter described may readily draw it out.

Floats 27 and 28 are preferably supported on long arms 29 and 30 respectively, and these arms are pivotally supported at the points 31 and 32 respectively upon the lower ends of the support 24. Integral with the arms 29 and 30 are short arms 33 and 34 respectively, upon which are pins 35 and 36 which engage in slots 37 and 38 formed in links 39 and 40 which are pivotally hung from the rack bar 25. Thus the arms 29 and 30 or the floats may be said to have a pin-and-slot lost motion type of connection with the rack bar 25 or indicator device proper. By means of this connection, it will be seen that the float which is the lowest down will be the one that operates the rack bar 25 and determines its position and thereby of course determines the position of the indicating hand 22. For instance, as shown in the drawing, the liquid has been practically exhausted from the right hand compartment of the tank and the float 28 consequently is at its lowest point. Through its connection with the rack bar 25 the float 28 pushes the rack bar to its upper limit and thereby indicates through the hand 22 that the tank is empty. Of course this indicates to the operator that the only remaining liquid in the tank is in the reserve compartment. It will be seen that the float 27 is somewhat higher than the float 28, but it has no effect upon the position of the rack bar 25 because of its pin-and-slot connection with that rack bar. It will be further observed that the arm 30 extends from the right hand compartment through an open-

ing or slot 41 in the partition 11, but as this opening 41 is above the opening 12 it does not affect the primary function of the said partition 11.

Various positions of the floats 27 and 28 are indicated in dotted lines.

It will be understood that if the liquid is to be withdrawn by suction, a proper vent will be provided in the tank, but if pressure is used the tank will be tightly sealed.

It will be further understood that various forms of the invention may be made without departing from the spirit or scope thereof.

Having thus described my invention, what I claim and desire to secure by Letters Patent is:

1. The combination with a tank having a plurality of compartments, of a single indicator device, and means controlled by the liquid level in the several compartments and adapted to operate the indicator to indicate the level in that compartment having the lowest level.

2. The combination with a tank having a plurality of compartments, of a movable indicator, and means operating in several of said compartments and operatively connected to said indicator so that the lowermost float will control the indicator to move in harmony therewith.

3. The combination with a tank having a plurality of compartments, of a movable indicator, and floats in said compartments operatively connected to said indicator so that the lowermost float will control the indicator to move in harmony therewith.

4. The combination with a tank having a plurality of compartments and liquid level responsive means for each compartment, of means controlled selectively by the responsive means of the compartment having the lowest liquid level to indicate such level.

5. The combination with a tank having two compartments and means for withdrawing liquid from either of said compartments separately, of liquid level responsive means for each compartment, and means controlled selectively by the responsive means of the compartment having the lowest liquid level to indicate such level.

6. The combination with a tank having two compartments and means for withdrawing liquid from either of said compartments separately, of a single movable indicator and means for operating the indicator to indicate the lower liquid level of said compartments.

7. An indicator means comprising a movable indicator and a plurality of means for operating said indicator so that the lowermost float will control the indicator to move in harmony therewith.

8. An indicator means comprising a movable indicator and a plurality of floats connected to operate said indicator so that the lowermost float will control the indicator to move in harmony therewith. 5
9. An indicator means comprising an indicator device, a plurality of floats, and a pin-and-slot type of lost motion connection between each of said floats and the indicator device. 10
10. An indicator means comprising an indicator device, a plurality of floats, pivotally supported arms connected to said floats, and pin-and-slot lost motion connections between said arms and said indicator device. 15
11. An indicator means comprising an indicator device, a float, and a pin-and-slot lost motion type of connection between said float and said device. 20
12. The combination with a tank having a partition separating the liquid below a given level, of an indicator mechanism adapted to indicate the liquid level of the tank as a whole down to said given level and to indicate the level on one side only of said partition beyond that point. 25
13. The combination with a tank having a partition separating the liquid below a given level, of an indicator mechanism adapted to indicate the liquid level of the tank as a whole down to said given level and to indicate the lower level of the liquid below said given level. 30
14. The combination with a tank, of a plurality of liquid level responsive devices therefor, and means controlled selectively by the responsive devices for indicating the liquid level of the shallower portion of the liquid in the tank when the latter is inclined. 35
15. The combination with an elongated tank, of an indicator, a float adjacent each end of the tank, and pin-and-slot connections from said floats to the indicator. 40
16. The combination with a tank having a partition therein dividing it into two compartments, of an indicator mechanism comprising a support secured to and extending above and below the upper wall of the tank, an indicator device mounted at the upper end of said support, float devices pivotally supported at the lower end of said support and extending into the respective compartments, and connections from said float devices to the indicator device whereby the latter is controlled by the float having the lower level. 45 50 55
17. The combination with a tank having a partition therein dividing it into two compartments, of an indicator mechanism comprising a support secured to and extending above and below the upper wall of the tank, an indicator device mounted at the upper end of said support, float devices pivotally supported at the lower end of said support and extending into the respective compartments, and pin-and-slot connections affording lost motion from said float devices to the indicator device whereby the latter is controlled by the float having the lower level. 60 65 70
18. The combination with a tank having a partition which is effective for separation of liquid part way upwardly only from the bottom thereof, of an indicator unit mounted on the top of the tank independently of said partition and having floats adapted to extend downwardly into the tank on either side of said partition. 75
19. The combination with a closed tank having a partition therein dividing it into two compartments, of an indicator mechanism comprising a support secured to and extending downwardly from the upper wall of the tank, an indicator on said support, and float devices connected to said indicator and extending from said support into the respective compartments. 80 85
20. The combination with a tank, of an indicator mechanism comprising an indicator device, a plurality of floats and a pin-and-slot type of connection between each of said floats and the indicator device, such connection being so formed that the lowermost float will control the movement of the indicator device. 90 95
21. The combination with an elongated tank, of an indicator, a float adjacent each end of the tank, and lost motion connections from said floats to the indicator. 100
22. An indicator means comprising an indicator device, a plurality of floats, and a lost motion connection between each of said floats and the indicator device. 105
23. An indicator means comprising an indicator device, a float, and a lost motion connection between said float and said device. 110

In testimony whereof I affix my signature in the presence of two witnesses.
